CLAIM

The ornamental design for a removable patch holder, as shown and described.

DESCRIPTION

FIG. 1 is a top plan view of the removable patch holder showing my new design;

FIG. 2 is a bottom plan view thereof;

FIG. 3 is a right side view thereof;

FIG. 4 is a left side view thereof;

FIG. 5 is a top elevational view thereof;

FIG. 6 is a bottom elevational view thereof;

FIG. 7 is a top perspective view thereof; and,

FIG. 8 is another perspective view shown with environment. The broken line showing of an apron in FIG. 8 illustrates environmental subject matter and forms no part of the claimed design.

1 Claim, 5 Drawing Sheets(56)
